UNITED STATES PATENT OFFICE.

RALPH L. SKINNER, PERCY C. WALRATH, AND EDMOND H. LAMBERT, OF DETROIT, MICHIGAN, ASSIGNORS TO SKINNER AUTOMOTIVE DEVICE COMPANY, INC., OF DETROIT, MICHIGAN, A CORPORATION OF CALIFORNIA.

INTERNAL-COMBUSTION-ENGINE-CYLINDER LUBRICATION.

Application filed September 21, 1925. Serial No. 57,480.

Under certain circumstances, as for instance when an internal-combustion engine is first started with the parts and the lubricating oil rather cold, it is desirable to supply an excess or adequate quantity of the lubricant to the cylinders to prevent their scoring and to aid generally in the lubrication operation.

This invention provides for the accomplishment of this beneficial result and it further supplies means for cutting off such superfeed of the oil as soon as the motor parts have become heated sufficiently so that the cylinders will be properly lubricated by the ordinary system of the motor.

In the present preferred embodiment of the invention, such surplus oil is fed to the cylinders through passages in the connecting-rods and the latter are equipped with thermostatic means to cause a cessation of such super or extra lubrication as soon as the parts of the motor have reached such a temperature that the normal lubrication will supply a proper quantity of oil to the cylinders.

To permit those trained in this art to understand this novel invention and the several advantages accruing from its employment, in the accompanying drawing, forming a part of this specification, and throughout the several views of which like reference numerals have been used to designate the same parts, a desirable and preferred embodiment of the invention has been illustrated in detail.

In this drawing:

Figure 1 is a vertical section through an internal-combustion engine equipped with the new features of construction;

Figure 2 is a partial, longitudinal section through one of the connecting rods; and

Figure 3 is a transverse or substantially horizontal section through the connecting-rod on the line 3-3 of Figure 2.

By reference to this drawing, it will be perceived that the internal-combustion engine is of the usual or conventional form and consequently its well-known structural elements and characteristics need not be described except in so far as they concern the present invention.

The motor cylinder is characterized 11, its crank-case 12, the piston 13 and the crank-shaft 14, the latter being hollow for

the forcing of the lubricant through its bore 15 to the several bearings as is customary in many constructions of this style.

Each connecting-rod 15, of which only one of the multi-cylinder engine is illustrated, has a lengthwise, cylindrical passage 16 therethrough, and each such channel or hole accommodates a spiral or coiled, bimetal thermostat 17 of well-known form, the lower end of which is secured to a sleeve 18 fastened or anchored in that end of the passage communicating with the interior of the crank-shaft through its corresponding lateral opening or connecting passage 19, the Babbitt metal of the connecting-rod bearing being characterized or designated 21.

The other or upper end of the thermostat carries a sleeve 22, of slightly larger diameter than the thermostat, snugly fitting in and revoluble in the bore 16, such bushing or sleeve having opposed, lateral, outlet ports 23, 23 adapted when the motor or engine is cold to register with companion cross ports or openings 24, 24 through the walls of the connecting-rod.

A convenient way of making this structure is to insert and fasten the thermostat inside of the connecting-rod as stated, and, then, while the parts are chilled or cooled to an appropriate temperature, for example zero degrees (0°) Fahrenheit, the aligned or registering ports 23 and 24 are drilled through the connecting-rod and thermostat sleeve walls.

Thus, when these parts are cold, the ports are open, and when such parts are warm or hot by reason of the expansion of the thermostat and the resulting turning of the registered sleeve 22, the ports are automatically closed.

The upper end of passage 16 communicates with and supplies lubricant for the wrist-pin bushing 25 as will be readily understood.

Oil from the pump line is supplied under pressure to the interior of the crank-shaft 100 from which it flows to the several bearings and to the passages up the connecting-rods for the lubrication of the wrist-pin bushings at their upper ends.

When the motor and oil are cold and the latter of somewhat thick consistency, there is small chance of the lubricating oil working out of the connecting-rod bearings and

splashing on to the cylinder walls and hence under such circumstances these walls are not properly lubricated.

It is to overcome this objection that the 5 thermostatically-controlled ports have been provided, and, accordingly, when the engine and the lubricant are cold, the ports 23 and 24 are open and the oil is pumped or played out through them directly on to the cylinder walls, the wrist-pin bushings under such 10 circumstances creating enough back pressure on the oil to effect its delivery through the connecting-rod openings in the manner stated.

15 Just as soon as the motor warms up, for instance to a temperature of sixty degrees (60°) Fahrenheit, the oil will pass by the bearings and on to the cylinder walls.

To prevent over oiling under such conditions, the thermostat, by expanding, turns the sleeve 22 and closes the holes through the sides of the connecting-rod thus cutting off this extra supply of oil which is not then needed.

20 25 In other words, surplus or extra oil is played or fed on to the cylinder walls while they are cold and before the normal lubricating system has become efficient after which the supply of auxiliary oil is automatically terminated.

An appliance of this kind is particularly 30 35 advantageous to temporarily or preliminarily supplement the action of the force-feed lubrication system and it overcomes one of the recognized serious disadvantages of the latter.

The new structure having once been installed in a motor, its action is entirely automatic and it requires no attention on the 40 part of the operator who is assured that the engine is receiving adequate, but not undue lubrication under all conditions.

The advantages accruing from the employment of a construction of this character 45 are more or less manifest and those skilled in this art will readily understand that many minor mechanical changes may be made in the one embodiment of the in-

vention presented and still be within the purview of the invention as defined by the 50 appended claims and without the loss of any of its material benefits and advantages.

We claim:

1. In an internal-combustion engine, the combination of the engine-cylinder, the reciprocal piston therein, the crank-shaft, the connecting-rod associated with said piston and crank-shaft and having a passage 60 therein with means for delivering the contents of said passage on to the cylinder wall, means to supply lubricant to said connecting-rod passage, and automatic means governing the discharge of said lubricant through said delivery means.

2. In an internal-combustion engine, the combination of the engine-cylinder, the reciprocal piston therein, means to lubricate said cylinder and piston, the crank-shaft, the connecting-rod associated with said piston and crank-shaft and having a 70 passage therein with means for delivering the contents of said passage on to the cylinder wall, means to supply lubricant to said connecting-rod passage, and thermostatic means automatically governing the discharge of such lubricant through said delivery means.

3. In an internal-combustion engine, the combination of the engine-cylinder, the reciprocal piston therein, means to lubricate said cylinder and piston, the crank-shaft, the connecting-rod associated with said piston and crank-shaft, said connecting-rod having a lengthwise passage therein 80 with a lateral discharge port to direct the delivery of the contents of such passage on to the engine cylinder, a spiral thermostat in said passage controlling said connecting-rod discharge port, and means to supply lubricant to said connecting-rod passage.

In witness whereof we have hereunto set our hands and seals.
